(57) **CLAIM**

The ornamental design for a lip balm holder with clip as shown and described.

DESCRIPTION

FIG. 1 is a FRONT elevational view of a lip balm holder showing my new design;

FIG. 2 is a BACK elevational view thereof;

FIG. 3 is a SIDE elevational view thereof with a ring attached;

FIG. 4 is a TOP elevational view thereof;

FIG. 5 is a BOTTOM elevational view thereof;

FIG. 6 is a perspective view thereof;

FIG. 7 is another perspective view thereof; and,

FIG. 8 is a FRONT elevational view thereof in a configuration of use.
The broken lines in the drawings show environmental structure and form no part of the claimed design.
